United States Patent Office

Des. 179,042
Patented Oct. 23, 1956

179,042

LIGHTER

Kenneth N. Van Norman, Silvis, Ill.

Application February 13, 1956, Serial No. 40,131

Term of patent 14 years

(Cl. D48—27)

FIG. 1

I claim:

The ornamental design for a lighter, as shown.
